(57) **CLAIM**

The ornamental design for a boot pad, as shown and described.

DESCRIPTION

FIG. 1 is a bottom plan view of the boot pad showing my novel design;

FIG. 2 is a top plan view thereof;

FIG. 3 is a left side view thereof;

FIG. 4 is a right side view thereof;

FIG. 5 is a front elevational view thereof;

FIG. 6 is a rear elevational view thereof;

FIG. 7 is a top perspective view of the boot pad of the present invention; and,

FIG. 8 is a bottom perspective view of the boot pad of the present invention as shown mounted to an ankle/foot orthosis.

The broken lines shown in FIG. 8 are for illustrative purposes only and form no part of the claimed design.
